UNITED STATES PATENT OFFICE

2,661,839

SAND CLASSIFYING APPARATUS

Leroy F. Bush, Edwardsville, Kans.

Application February 6, 1950, Serial No. 142,698

5 Claims. (Cl. 209—17)

1

The present invention relates to commercial sand cleaning or washing and classifying equipment, and the primary object in view is to devise an improved form of apparatus designed to carry out the required operation of cleaning and classifying sand material, as received from dredging apparatus, in a more efficient manner and better adapted for commercial purposes, and in conformity with the practice usually prevailing in plants of sizable producing capacity.

It is also an object of the invention to provide apparatus of this character which is of a more economical construction, and having the parts thereof more accessible for maintenance or repair, as well as such manual regulation or control as is required for its normal operation.

In general, it is sought to devise an improved construction and arrangement of apparatus for conducting, under dredge-pumping pressure, a flow of dredge material, having a sand and gravel content, to the washing and classifying apparatus—which is comprised of multiple units as required for properly grading the sand and gravel output, together with an improved valve arrangement and construction whereby the operation of the flow and discharge of the material is effectively controlled for maintaining a continuous and uniform output of the respective grades or classifications of the sand material.

It is also sought to provide a construction of this character in which the separation of the material in to the main grades of relatively fine sand material is supplemented by a subsequent separating process in which the coarser gravel ingredients of the main flow are retrieved therefrom before discharge into the final waste flow from the apparatus.

With the foregoing general objects in view, as well as various minor objects as well appear in the course of the detail specification, the invention will now be described by reference to the accompanying drawings illustrating one preferred form of construction which has been found to be practical and efficient for the embodiment of the proposed improvements, after which those features and combinations deemed to be novel and patentable will be particularly set forth and claimed.

In the drawings—

Figure 1 is a view in elevation illustrating an apparatus arranged and constructed in accordance with the present invention;

Figure 2 is a plan view of the same;

Figure 3 is a sectional plan view, representing a section taken on the line 3—3 of Figure 1 (all 55

the supporting framework structure being omitted);

Figure 4 is a vertical sectional view, representing a section taken on the line 4—4 of Figure 1 (on an enlarged scale);

Figure 5 is a detail sectional view, as indicated by the section line 5—5 in Figure 3; and

Figure 6 is a sectional view, representing a section following the section line 6—6 shown in Figure 1.

The present invention and application relate to improvements in the type of apparatus illustrated and described in my prior Patent No. 2,337,446, dated December 21, 1943.

Referring to the accompanying drawings, I have herein illustrated the improved apparatus as comprising a flume member 10 for receiving the dredge material, as discharged from an intake connection 11 which conducts said material from the source of supply under the dredge or working pressure of the dredge pumping equipment. The flume member 10 is mounted in overhead relation to a series of washing and classifying units, where said dredge material, having the usual sand and gravel ingredients, is discharged into a series of hopper units 12 corresponding to the several grades or classifications for which the apparatus is designed. Accordingly, each of the hopper units 12 is arranged to discharge through an opening 14 into a collecting chamber 16 at the lower end of a cylindrical casing 18—the said construction, comprising the flume member 10 and hopper and casing units, being all supported by means of suitable framework indicated generally by the reference numeral 20, in Figures 1, 2 and 4.

Each of the cylindrical casing units 18 is formed with a conical bottom portion 22 having a discharge opening 24, the passage through which is controlled by a valve member 26 carried by the lower end of a valve stem or rod 28. Each valve stem or rod 28 extends upward through a tubular guide 30 supported by radial brace elements 32 within the casing 18, and the upper end portion of each rod 28 is provided with a float element 34 adjacent to the upper end of the corresponding casing unit 18. Each valve stem or rod 28 further extends through the upper end of the corresponding casing 18 as well as on through a corresponding tubular closure element 30' and an upper platform 35 supported by the framework 20 directly above the several casing units 18, where the upper end of each valve rod or stem 28 is pivotally connected with a rocker arm or lever 36. The series of rocker arms or

levers 36 are fulcrumed, as indicated at 38, upon the framework 20, and at their outer ends are provided with cable operating connections 40 to suitable winch devices 42 located on a lower platform structure 44 also supported by the framework 20, as shown in Figures 1 and 4. By means of these connections to the valves 26 the latter may be conveniently regulated manually for properly setting and holding of said valves in either closed or various partially open positions with reference to the discharge openings 24, as represented in Figure 4. It will be noted that each valve has a maximum open position as limited by the engagement of the corresponding float 34 with the upper end of the tubular member 30.

Each of the casing units 18 is further provided with a drain outlet pipe 46 having an inlet opening 48 at approximately the level of the lowermost position of the corresponding float element 34, for affording a drainage action from the collecting chambers 16 as required for the float-control operation of the valves as hereinafter explained. The lower or outlet ends of the several drain tubes 46 are positioned for discharging into a common discharge flume or trough 50 extending alongside all the units of the installation, as illustrated in Figures 3 and 4.

The material or output from the several collecting chambers 16 is adapted to be discharged into tiltable hopper members 52, each of which is supported by a rocking axle 53 provided with a manually operable arm 54, whereby the hoppers may be rocked into either of two positions, i. e., for dumping the contents thereof into a common receiving trough 55 supported by the framework 20, or into a discharge chute 56 mounted upon said trough 55 in position for receiving the material from the corresponding hopper 52 and conducting said material over into the discharge flume or trough 50—see Figures 3 and 5. The trough 55 is constructed to provide inclined portions converging to a common discharge point where it empties into a downwardly projecting chute 58 carrying a hinged delivery spout 60 for conveying the output to a suitable carrier—as is common to such apparatus, a cord 62 operating over a guide pulley 63 and carrying a counterbalance weight 64 being provided for maintaining said spout 60 normally in raised and inoperative position.

At its intake or receiving end, the flume member 10 is provided with a baffle device 65 spaced from the bottom of the flume or trough 10, as indicated at 65', from which point the bottom of the flume is constructed to conduct the material in a slightly downward course, corresponding to the consecutively lowered positions of the series of hopper units 12, as represented in Figure 1; and each of the openings 14 into said hopper units is provided with a suitable screen panel 66 for screening the dredge material and allowing passage of only such graded particles of the sand material as is desired to be collected in the several sand collecting chambers 16.

At its outlet end the flume or trough member 10 is further provided with a screen and panel structure for the final separation and retrieving of the coarser gravel particles from the flow of dredge material. This construction comprises a collecting chamber 68 underlying the final screen panel 66 of the flume bottom and provided with a baffle device 70 separating said chamber from an inclined screening chamber 72 communicating with and discharging into a gravel collecting chamber 74 located in a vertical spout struc-

ture 76 through which the discharge or waste flow of material is conducted from the discharge end of the flume or trough 10 to the upper end of the flume or trough 50—as represented in Figures 1, 4 and 6.

The screening chamber 72 is formed by an inclined panel 78 extending from the top of the collecting chamber 68 to the outer side of the chamber 74, and a suitable screen panel 80 extending in spaced relation to said panel 78 and from the bottom of said chamber 68 to the inner side of the chamber 74 as well as in slightly spaced relation to the lower edge of the baffle device 70—see Figures 1 and 6. The baffle member 78 is movably mounted as shown, to permit access to the interior of the screening chamber 72, when necessary, as for mounting or replacement of the screen 80; and a suitable discharge spout 82 is provided at the lower or outlet end of the collecting chamber 74.

The framework or supporting structure also includes the usual ladder means 84 for use by workmen and enabling them to reach the various different levels of the apparatus, as indicated in Figures 1 and 4.

In my prior patent, above referred to, the sand washing and classifying apparatus employed a float-controlled valve construction which regulated the flow of sand material through a collecting chamber which surrounded the valve-operating means, thus requiring a collecting chamber of such proportions as to incorporate the valve-control assembly as the interior or central core structure of the complete washing and classifying unit, and including an overflow or discharge connection from the float chamber to the waste trough or outlet. The present improved construction is designed to incorporate all the requisite control features of the valve float control assembly in separate relation to the sand collecting chamber, so that the size or proportions of the latter may be determined independently of the operational requirements of the valve control means and the latter left free and accessible for any service or maintenance requirements as may arise in the operation of the equipment. The valve control operation remains substantially the same as in my prior construction; the purpose being to maintain a normal and substantial flow of solid, sand material from the hopper chamber 12 through the opening 14 into the collecting chamber 16 and out past the valve 26, for which purpose the sand flow must be sufficient to practically exclude any accumulation of water in said chamber beyond the drainage capacity of the outlet 48 to the overflow pipe 46. When the solid content of the sand flow diminishes to such an extent that the water content entering through the upper portion of the opening 14 into the chamber 16 exceeds the drainage overflow therefrom, the continuation of such diminished sand flow will result in enough water entering said chamber to lift the float 34 and thereby close the discharge valve 26 until an increase in the sand or solid content of the flow serves again to reduce the amount of water passing through opening 14 to the point where the drainage action from the chamber 16 will permit lowering of the float member to reopen the valve, so that a full normal flow of the sand material will be resumed. This control operation continues until a balanced flow condition is attained, so that the discharge flow of the material from said chamber 16 through its outlet 24 becomes practically continuous and uniform. In other words, the float control operation

is of a character serving as a compensating factor for accommodating the flow of the material into the unit and regulating such flow in such a way as to result in a substantially continuous and uniform flow at the discharge point of each grading outlet from the several valve-controlled units of the installation.

The arrangement of the several grading units of the installation in discharge relation to a common discharge flume or trough and providing same with individual hopper discharge means for separately controlling the discharge of the output from the several grading units enables the operator to regulate and selectively control the relative percentages or fractions of the graded contents for any particular or special run of the material to be delivered by the apparatus according to any given requirements or specifications.

The grading or classifying construction provided at the tail end of the flume member 10 is designed as a further refinement of the construction for retrieving the coarser gravel particles of the material flow, and as a by-product in connection with the waste flow of the material, after separation of the relatively finer sand content of the dredge flow. This is accomplished by an extension of the screening operation of the dredge flow and an effective separation of the said gravel portion of the material, by the means or structure provided and illustrated herein, prior to the final discharge of the waste flow into the flume or trough 50, and thus constitutes a valuable adjunct to the primary purposes and functions of the main or primary classification equipment as herein outlined.

The apparatus as shown further preserves all the important advantages characterizing my prior equipment, including a construction which requires very little head room—being initially under the pressure as delivered from the dredge pumping apparatus, and the resultant or final operation of the installation provides for a complete removal of all undesired waste or refuse matter from the flow of the original dredge stream.

While the foregoing represents one practical and efficient form of construction for embodying the proposed features of improvement as required for accomplishing the desired objects of my invention, it is apparent that the construction illustrated is susceptible of various minor changes and modifications within the spirit and scope of my said improvements, and I therefore wish to be understood as reserving the right to make whatever changes or variations may fall within the scope of my invention as defined by the appended claims.

What I claim is:

1. Sand cleaning and classifying apparatus comprising a flume for the flow of dredge material, a material receiving hopper chamber underlying said flume and separated therefrom by a screening means intercepting the flow of material entering said chamber, a separate flow-controlling chamber in exterior and side by side relation to said hopper chamber and provided with a discharge outlet for regulating the flow of said material from said second chamber and also having a material-receiving opening communicating with the lower end of said hopper chamber, and a valve controlling the flow through said discharge outlet and provided with float-control means located above said material-receiving opening and actuated in accordance with the liquid level of the contents within said flow-controlling chamber.

2. Sand cleaning and classifying apparatus comprising a flume for the flow of dredge material, a material receiving hopper chamber underlying said flume and separated therefrom by a screening means intercepting the flow of material entering said chamber, a separate flow-controlling chamber in exterior and side by side relation to said hopper chamber and provided with a discharge outlet for said material and also having a material-receiving opening communicating with the lower end of said hopper chamber, and a valve controlling the flow through said outlet and provided with a float member located above said material-receiving opening and controlling the movement of said valve in accordance with the liquid level of the contents within said second chamber, said flow-controlling chamber having a drainage outlet at the lower limit of movement of said float member.

3. Sand cleaning and classifying apparatus comprising a flume for the flow of dredge material, a material receiving hopper chamber underlying said flume and separated therefrom by a screening means intercepting the flow of material entering said chamber, a separate flow-controlling chamber in exterior and side by side relation to said hopper chamber and provided with a discharge outlet for said material and also having a material-receiving opening communicating with the lower end of said hopper chamber, a valve controlling the flow through said outlet and provided with a float member located above said material-receiving opening and controlling the movement of said valve in accordance with the liquid level of the contents within said float-controlling chamber, and means limiting the movement of said float member in accordance with the fully-open and fully-closed positions of said valve, said flow-controlling chamber having a drainage outlet at the lower limit of movement of said float member.

4. Sand cleaning and classifying apparatus comprising a flume for the flow of dredge material, a plurality of material receiving hopper chambers underlying said flume and separated therefrom by screening means intercepting the flow of material entering said chambers, separate flow-controlling chambers in exterior and side by side relation to said hopper chambers and provided with discharge outlets for regulating the flow of material therethrough and also with material-receiving openings communicating with the lower ends of the respective hopper chambers, valves for controlling the flow through the respective discharge outlets and provided with float-control means actuated in accordance with the liquid levels of the contents within said flow-controlling chambers and including float members located above the corresponding material-receiving openings, and conduit means in receiving relation to said discharge outlets from said flow-controlling chambers and provided with means for selectively receiving the material as discharged from the several flow-controlling chambers.

5. Sand screening and classifying apparatus comprising a flume for the flow of dredge material, means providing a hopper chamber underlying said flume and separated therefrom by screening means intercepting the flow of material from said flume into the hopper chamber, a casing adjoining said hopper chamber in side by side relationship thereto and providing a float

chamber in the upper portion of said casing and also a material-collecting chamber in its bottom portion having a material-receiving opening communicating with the lower end of said hopper chamber, the bottom of said material-collecting chamber having a discharge opening provided with a valve regulating the flow therethrough, and a float member mounted within said float chamber above said material-receiving opening and connected with said valve for controlling the movement thereof in accordance with the liquid level of the contents within said float chamber

and the latter having a liquid discharge outlet at the lower limit of movement of said float member.
